UNITED STATES PATENT OFFICE.

SALVATORE STELLA, OF BROOKLYN, NEW YORK.

HEEL-CLAMPING MACHINE.

1,282,971.

Specification of Letters Patent.

Patented Oct. 29, 1918.

Application filed October 16, 1917. Serial No. 196,856.

To all whom it may concern:

Be it known that I, SALVATORE STELLA, a subject of the King of Italy, residing at Brooklyn, county of Kings, and State of New York, have invented new and useful improvements in Heel-Clamping Machines, of which the following is a specification.

This invention relates to a machine in which a clamping device is essentially employed to securely hold a wooden high French or Cuban glued heel to the rear of the shoe until the glue sets.

The invention is designed to provide means controlled by the operator for moving a work support in a concentric circle and means for oscillating the support about its axis.

The object of the invention is to rotate the work support so as to arrange the work or shoe in a convenient position to operate the clamping devices.

Another object of the invention is to mount the support on a carriage so that when the glued heel is clamped in its proper place on the upper, the carriage can be moved out of the way and the next carriage with its support brought into action.

The invention comprehends a plurality of carriages each being provided with a work support and means for supplying a blast of air directly against the glued heels while they are traveling around the track, thus when the first support reaches the starting point the glue will be dried and the shoe can be removed.

The novel features of the invention are more fully described in the following specification and claims and illustrated in the accompanying drawings in which:

Figure 1 represents a plan view of a machine embodying this invention.

Fig. 2 is a front elevation of a latch device.

Fig. 3 is a vertical section taken along the line $z-z$ of Fig. 1.

Fig. 4 is a front elevation of a carriage and work support.

In these drawings the letter a designates a column having a spider b secured to the upper part of the column. A circular track c is fixed on the ends of the spider arms

and it has channels d located on the inner and outer portion of the track. An upwardly curved portion e in the track leads to the first position on the track.

A carriage consisting of a pair of horizontally positioned idler rollers f is made to engage the channels in the track. Caps g bolted to the lower portion of the carriage will journal the rollers relative to the channels. Side rollers h best seen in Fig. 4, will ease up the lateral friction on the channels and give easier rotation to the carriage. A post i having a socket j in its upper end, forms the upper part of the carriage.

A work support including a shaft k provided with a pin m coacting with the socket can freely revolve on the post. On the upper end of the shaft is removably mounted a work holder n equipped with a pin o to engage a hole in the last p fitted into a shoe upper q of ordinary construction. The holder n is slidably mounted on the shaft so that it can be removed and other holders substituted for different shapes of lasts. The holder as indicated in Fig. 4, has a rim r to prevent lateral movement of the last relative to the holder.

The clamp for pressing the heel s downward after its upper portion is coated with glue consists of a screw t having a handle u for rotating the screw up or down. The screw engages a threaded upper part of a yoke member v secured to the side of the shaft. The lower end of the screw can turn freely on a bifurcated head w pivoted at x to an intermediate coupling y . The coupling is in turn connected at z to a base member 13 forming the lower end of the clamp. The base member can be provided with a leather cushion 14 to contact with a lift or tap fixed on top of the heel.

By this arrangement the base member 13 can swivel to fit itself to the top surface of the heel, while the screw remains in its vertical position. A guide rod 15 slidably coacting with a lug 16 on the side of the head will prevent the head and coupling from revolving when the screw is operated.

Slidely connected to an extension of the yoke v is a plunger 17 pivoted at 18 to a

cam lever 19 arranged on the top of the extension. The lower portion of the plunger 17 is bifurcated to slide over a washer 20 loosely mounted on a rod 21 with a coil 5 spring 22 mounted thereon. The lower end of the rod carries a presser foot 23 provided with a leather cushion to contact with the rear portion of the shoe. The yoke extension is provided with a slot in which the 10 plunger 17 is loosely arranged to guide it up or down, and a spring 17' normally forces the plunger against the wall of the slot to eliminate play room. The slot permits the plunger to move laterally against 15 the action of the spring, thus compensating for the arc of oscillation transmitted to the pivot 18 when the cam lever is actuated. The upper end of the rod 21 is fixed to the plunger and the upper face of the washer 20 contacts with the lower part of the extension, so that when the spring is compressed the washer will be forced against 25 the lower part of the extension.

This device by the downward and forward pressure of the coiled spring will hold the heel against backward movement when it is placed on to the upper as shown in Fig. 3. When it is desired to release the presser foot from contact with the heel, the cam lever is 30 operated to bring the highest point of the cam opposite the handle, on to the top of the extension thus lifting the rod and compressing the spring to move the presser foot out of action or away from the heel. By 35 rotating the screw δ the clamp is disengaged or raised from the top of the heel and the shoe can then be readily removed.

A latch including a vertical pin 24 passes through a hole in the forward portion of 40 the circular track. This pin is normally pressed upwardly by a coiled spring 25 and when the carriage is moved to a position over the pin or at the front part of the machine, the pin will be pressed downward by 45 a lug 26 fixed to one side of the carriage. When the carriage reaches the center of the pin 24 it will snap into engagement with a hole in the post and hold the carriage against movement. The pin can be unlocked 50 from the carriage by a lever or treadle 27 located within easy reach of the operator.

The work support λ and the clamping device above it can oscillate about the post λ , and hence when it is desired to remove or 55 place a shoe in position on the support, it is given a half turn as indicated in Fig. 1 with the cam lever 19 outside. After the shoe is in position the clamping device can be turned with the cam handle and the back 60 of the heel pointing toward the axis of the track. Any number of the clamps can be mounted on the track depending on its size, for example on the size shown in the drawing, the number would be about 24 each

being pushed in the direction of the arrow 65 along the track until the starting point is reached by the foremost.

An air drum or tank 29 is shown mounted on the top of the column. The drum has nozzles 30 projecting from the side of the 70 drum and pointing toward the heels of the shoes while they travel around the track. A pipe 31 connected to the bottom of the drum and leading from a blower, pump, or other air supply will conduct air pressure 75 into the drum. The nozzles direct the air in a constant stream on to the backs of the heels on a line with the glued joint so that when a clamp with its shoe travels around the track, when it arrives at its starting 80 point, the glue will be dried and the shoe can be removed.

I claim:

1. In a heel clamping machine the combination with a carriage and a track therefor, 85 of a shoe support rotatively mounted on the carriage, a screw carried by the support, and a movable base member connected to the screw for coaction with the heel of the shoe.

2. In a heel clamping machine the combination with a carriage and a track therefor, 90 of a shoe support rotatively mounted on the carriage, a screw carried by the support, and a swiveling base member connected to the screw for coaction with the heel tread of 95 the shoe.

3. In a heel clamping machine the combination with a carriage and a track therefor, 100 of a shoe support rotatively mounted on the carriage, a screw clamp carried by the support, and a spring presser foot to engage the back of the heel.

4. In a heel clamping machine the combination with a carriage and a track therefor, 105 of a shoe support rotatively mounted on the carriage, a screw clamp carried by the support, a spring presser foot to engage the back of the heel, and a lever for operating the presser foot.

5. In a heel clamping machine the combination with a carriage and a track therefor, 110 of a shoe support rotatively mounted on the carriage, a screw clamp carried by the support, a spring presser foot to engage the back of the heel, and a cam lever for operating 115 the presser foot.

6. In a heel clamping machine the combination with a track, of a carriage mounted on the track, a spring controlled latch for locking the carriage to the track, a shoe support rotatively mounted on the carriage, a screw carried by the support, a swiveling base member connected to the screw for coaction with the tread of the heel, a spring presser foot carried by the support to engage the back of the heel, and a cam lever for operating the foot. 120

7. In a heel clamping machine the combi-

nation with a circular track, of a plurality of carriages mounted on the track, a shoe support connected to each carriage, and means including a tank located within the track for blowing a current of air on to the heel portions of the shoes.

In testimony whereof I have hereunto set

my hand in the presence of two subscribing witnesses.

SALVATORE STELLA.
